UNITED STATES PATENT OFFICE.

EMMIT G. LATTA, OF SYRACUSE, NEW YORK.

TYPE-WRITING MACHINE.

1,253,258.

Specification of Letters Patent. Patented Jan. 15. 1918.

Application filed May 24, 1913. Serial No. 769,581.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to improvements in typewriting machines and more particularly to mechanisms employed in front strike or visible writing typewriters for enabling the paper platen to be shifted to place it in printing relation with one or another of the different sets of type on the type bars, and to other associated parts of the machine.

The objects of the invention are to produce a shifting support for the platen carriage of front strike or visible writing typewriters that enables the carriage to be made lighter than is usual in machines having a shifting platen; that is free from sliding friction; that is comparatively inexpensive to manufacture and assemble in the machine and can be quickly dismounted; also to provide actuating connections for certain parts mounted on the carriage and shifting support that permit such parts to be actuated from the keyboard equally well when the carriage is in one or another of its different printing positions; and to otherwise improve the shift mechanism and associated parts of typewriting machines in the respects hereinafter described and set forth in the claims.

In the accompanying drawings consisting of four sheets:

Figure 1 is a longitudinal sectional elevation of a typewriting machine embodying the invention, in line 1—1, Fig. 2.

Fig. 2 is a plan view thereof, partly in section, omitting the carriage, and showing a different position of the mechanism for changing the throw of the ribbon vibrator.

Fig. 3 is a fragmentary transverse section thereof in line 3—3, Fig. 1, looking toward the front of the machine.

Fig. 4 is a plan view of the leg of the shift frame detached.

Fig. 5 is a sectional elevation of the shift frame and the swinging members therefor.

Fig. 6 is a fragmentary sectional elevation of the margin stop mechanism, showing the abutment in position to clear the margin stop.

Fig. 7 is a fragmentary transverse sec-

tional elevation of the margin stop mechanism, in line 7—7, Fig. 2.

Fig. 8 is a plan view on an enlarged scale, partly in section, of the ribbon vibrating mechanism, showing the parts in the same position as in Fig. 1.

A represents the stationary or main frame; B the paper platen, and C one of the series of pivoted type bars of the machine. These parts may be of any suitable construction, but are preferably constructed and arranged as in the Moyer typewriter, which is disclosed in various patents and pending applications in the name of Harvey A. Moyer, 70 Oscar C. Kayle and Emiss G. Latta.

As shown the main frame is provided with a top plate *a* which is detachably secured in place by screws, or other fastenings. The platen *B*, as usual, is journaled on a carriage arranged to travel horizontally crosswise of the machine. The complete carriage is not shown, as it is not essential to an understanding of this invention. It consists of end pieces or frames connected by a base frame or bar *b* and a front or scale bar *b'*. *b*² indicates the rack bar on the carriage which meshes with a pinion *b*³ connected to the carriage escapement, indicated at *b*⁴, for controlling the letter space movements of the carriage in the usual way. The type bars are pivotally mounted in an arc in any suitable way on an upright segment or support *c* which is fixed in the stationary frame, and are adapted to swing upwardly and rearwardly to make the impressions at the front portion of the platen. Each type bar is provided with a plurality of type, and the carriage is adapted to be shifted to place the platen in printing relation with one or another of the sets of type on the type bars.

The platen carriage is supported and adapted to travel horizontally on a shift frame *D* which is adapted to be shifted up and down for placing the platen in position for printing with one or another of the different sets of type. Instead, however, of arranging the shift frame to swing about pivots connecting the same directly to the main frame, as heretofore done in the Moyer machine, the shift frame is mounted so as to move substantially vertically up and down by supporting means in the nature of a parallel link motion consisting of upper and lower swinging links, members or parts, 110 each of which is pivoted to the main frame and to the shift frame.

- The shift frame D shown consists of an open cradle-like casting of rectangular form which has projections d' d^2 extending, respectively, forwardly and rearwardly from the middle portion of the frame, and is provided with opposed parallel hardened steel race bars or tracks d^3 d^4 between which and complementary race bars or tracks on the base bar b of the carriage are arranged ball bearings b^5 which support the carriage and guide it in its horizontal travel on the shift frame. The front projection d' supports the ribbon guide or vibrator, and the carriage escapement is mounted on the rear projection d^2 . The shift frame, constructed as described, is adapted to receive the carriage of the Moyer typewriter without change in any of the carriage parts, but the construction of the shift frame could be modified to adapt it to carriages of different constructions.
- E represents a leg or part which is rigid with and depends from the shift frame substantially midway between the ends thereof. For convenience in manufacture this leg consists of a separate casting provided with a forked upper end forming two flanges e which are rigidly attached to the shift frame by four screws e' . F and G represent, respectively, the upper and lower members or links of the supporting link motion for the shift frame. The upper link or member F shown consists of a bar extending transversely of the machine beneath the shift frame and provided at its ends with cross arms f which extend forwardly and rearwardly and are suitably pivoted at their front ends to the shift frame at f' and are suitably pivoted at their rear ends to lugs or standards f^2 rising from the rear portion of the top plate a of the main frame. The lower link or member G is suitably pivoted at its rear end to a lug or standard g rising from the lower rear portion of the main frame and is pivoted at its front end to the lower portion of the leg E. Preferably the lower end of the leg E is forked and provided with a fixed pivot g' , and the front end of the link G enters the forked lower end of the leg E and has an upwardly opening slot in which the pivot g' is removably seated. A spring g^2 , arranged between the link G and the rear part of the main frame, holds the front end of the link up against the pivot g' . The movement of the link G is limited by a stop or pin g^3 which the link is adapted to strike. Preferably, the pivots, connecting the front ends of the upper and lower swinging links or members F and G to the shift frame and leg E, are arranged in the same vertical plane, and the pivots connecting the rear ends of these swinging links or members to the main frame are also arranged in the same vertical plane, and the two links or members are of

the same length. The pivots at the front ends of the supporting links or members are, in the normal or lower position of the platen, slightly below the horizontal planes of the pivots for the rear ends of the links or members and are adapted to swing to a corresponding distance above said horizontal planes when the platen is shifted to its upper position. Thus the platen is raised and lowered in a substantially vertical direction and its two printing positions are directly over each other in the same vertical plane.

H H, Fig. 3, represent two coiled springs seated in cups h in the top plate a beneath the front end portions of the shift frame. The upper ends of the springs bear in sockets in the shift frame, and their lower ends are adjustably secured in holes in the bottoms of the cups h by set screws h' . The set screws enable the springs to be adjusted so as to counterbalance the weight of the shift frame and carriage with the nicety required to enable the carriage to be shifted easily and prevent its return by gravity sluggish.

The shift frame, mounted as described, is entirely supported by the swinging links or members and the springs H H, and in effect is adapted to float or rise and fall vertically, but it does not have any sliding connection with the main frame of the machine and is, therefore, free from sliding friction when shifting. The described floating support for the shift frame combines the advantages of the pivoted or oscillating shift frame, heretofore employed in the Moyer machine, and of a sliding shift frame, but it is free from the disadvantages incident to a sliding support. This construction has the advantage over constructions in which the platen is mounted to shift on the carriage that no part of the shift mechanism partakes in the horizontal travel or letter space movements of the carriage, and the weight of the carriage is only about one-half as great as those in which the shift is effected on the carriage by parts that travel horizontally with the carriage. The extra weight of such a carriage necessitates a carriage driving spring tension several ounces greater than a carriage of equal capacity which is mounted on a shift frame such as described which does not travel horizontally with the carriage. The actual difference in power required to set the carriage back for a new line is of vital importance, and the reduced wear and noise on the escapement are also important considerations. A sliding shift frame or support is prone to stick or bind in its guides and a very close and accurate fitting is essential, which renders it impossible to avoid sliding friction, thus causing the sliding support to work hard. The floating support described has the further advantage over the prior oscillating or piv-

oted shift frame support that the platen does not have to be shifted such a great distance to prevent smutting the work, because in the oscillating construction, as the type face the 5 pivotal axis of the shift frame they must be spaced farther apart than the type used with the above described floating support which moves substantially vertically. This materially reduces the weight of the outer 10 ends of the type bars and, therefore, lessens the exertion necessary to operate the type bars. With the floating or parallel link motion described, in which the front pivots move up above the horizontal planes of the 15 rear pivots to the same distance that they are normally below these planes, the printing line on the platen is in exactly the same relation to the type bars in both positions of the platen, except that one position is 20 higher than the other, and each of the two type on each type bar faces directly to the rear when it strikes the paper on the platen. The upper link or member F, consisting of the bar with the end cross arms f, is in effect 25 the same as a pair of rigidly connected links, or a simple rock shaft having rigid arms at its ends, and a frame or member of either such form, or other form, could be used without altering the action thereof. The 30 member is made in the form shown to avoid interference with nearby parts of the machine.

The shifting mechanism for moving the shift frame to shift the platen from one to 35 another of its printing positions is preferably substantially the same as that heretofore employed in the Moyer machine, and comprises a shifting cam I which is suitably pivoted at its lower end on the lower 40 rear part of the type bar segment, and an anti-friction roller i which is suitably journaled on the leg or member E of the shift frame and enters the cam slot of the cam I. The cam slot has an inclined middle portion 45 for shifting the shift frame and end portions shaped to prevent the shift frame and platen from vibrating at the end of the shift in either direction. K is a horizontal rock shaft which extends transversely of the machine under the key levers and is provided 50 at its central portion with a rigid arm k connected to the cam H by a link k' extending between the two central type bar hangers or bearings on the segment. The rock shaft is provided at opposite ends with rockers or arms k² which bear and are adapted to rock on the rear ends of shift levers K' which are pivoted between their ends and are provided at their front ends with operating finger keys. When either of the shift 55 keys is depressed the shaft K is rocked and acts through the arm k and link k' to move the cam I rearwardly and force the roller upwardly, thus moving the shift frame support, together with the shift frame and car-

riage supported thereby from the normal or lower position to the upper or shifted position. A spring k³ coiled about the rock shaft K acts to start the cam from its locked shifted position as soon as the shift key is released, and then the weight of the shift frame and carriage causes the return of these parts to the normal positions. The cam I and roller i are preferably located, as shown, substantially midway between the ends of the shift frame. The single leg or member E thus located and the single lower link or member G, hold the shift frame in proper position, just as well as if a pair of such links or members were employed at the opposite ends of the shift frame, and the single connection is lighter, less expensive and works with less friction. Another advantage of this construction is that it is quicker to assemble. The open seat or slot in the lower link or member G for the pivot on the leg or member E permits the shift frame to be removed from the machine, leaving the lower link or member in place.

L represents an abutment adapted to be struck by margin stops on the carriage for limiting the horizontal travel of the carriage. l indicates one of the margin stops, two of which are employed, adjustably secured on the front or scale bar b' of the carriage at opposite sides of the abutment. The abutment L is located in a vertical opening l' in the central front projection d' of the shift frame and is fixed to the inner end of a shaft l² which is suitably journaled on the front portion of the shift frame. A spring l³, Fig. 2, coiled about the shaft l² acts to normally hold the front end of the abutment up in line with the margin stops as seen in Fig. 1, and also holds it in the right hand portion of the opening l'. The abutment shaft is provided at its outer end with a rigid arm l⁴ which depends from the shaft in rear of the upright rear end of a rod M which extends forwardly to the key board 110 and is provided at its front end with a push key m. By pushing this key rearwardly the rear end of the rod M will engage the arm l⁴ and rock the shaft, thereby lowering the front end of the abutment L out of the path of movement of the margin stops. A suitable spring m', Figs. 1 and 6, returns the push rod M to its normal forward position. The abutment and its shaft shift with the shift frame when the latter is raised or lowered, but the lower end of the arm l⁴ is opposite the rear end of the push rod M in both positions of the shift frame so that the inward movement of the push key m will move the abutment to clear the margin stops 115 in just the same way in both positions of the shift frame.

N represents a ribbon guide or vibrator mounted to reciprocate vertically on the front projection d' of the shift frame, and 130

n is a vibrator lever for actuating the ribbon vibrator. The vibrator lever is fulcrumed beneath the abutment *L* in the forked upper end of the leg *E* of the shift frame and as seen in Fig. 1 has a short horn *n'* adapted in one position of the abutment to be engaged by a depending lug *n²* on the abutment. In the normal position of the abutment, shown in Figs. 1 and 7, the horn *n'* on the vibrator lever is located at one side of the lug *n²* on the abutment, and does not prevent the vibration of the vibrator lever. When, however, the margin stop at the right of the abutment *L* strikes the latter it moves the abutment to the left against the action of the spring *l³* thereby placing the lug *n²* of the abutment directly over the horn *n'* of the vibrator lever and locking the vibrator lever against movement. As the vibrator lever is connected to the universal bar which actuates the carriage escapement, as hereinafter described, this locks the carriage escapement, and forms what is commonly known as a line lock to prevent overprinting at the end of a line. If the abutment is lowered to clear the margin stop, as before explained, the spring *l³* will return the abutment to the right to its normal position, thereby releasing the escapement or line lock. But the abutment will be held down by the overlying margin stop and a few more characters can be printed, if desired. When the carriage is set back for a new line the spring *l³* will return the abutment to its normal elevated position as soon as it clears the margin stop, the abutment thus being ready to again arrest the travel of the carriage. When it is desired to print at the left of the established margin, the abutment is held down by the push key *m* while the carriage is set over to the right as far as desired, and as soon as the carriage has moved back to the left far enough for the abutment to clear the left hand margin stop, the abutment will spring up into normal position ready to lock the line by intercepting the opposite margin stop.

The universal bar *O* or element for causing the operation of the ribbon vibrator and carriage escapement when the type bars are actuated and the actuators *P* for the universal bar are arranged much the same as disclosed in Patent No. 1,018,062, granted Feb. 20, 1912, to Oscar C. Kayle, assignor, but instead of the universal bar being mounted on the underside of the top plate *a*, as shown in said patent, the universal bar or rock shaft *O* is journaled in depending bearing brackets *o* on the forked head of the leg *E* of the shift frame, so that the universal bar moves with the shift frame. The actuators *P* consisting of curved bars arranged over the type bar bearings in position to be struck and moved by the type bars when the latter approach the platen, are carried by rods *p*

suitably mounted on the under side of the top plate *a* to move forwardly and rearwardly. The supporting rods *p* for the actuators *P* are provided with upright rear extremities *p'* adapted to engage the laterally enlarged extremities of arms *p²* depending from the universal bar for rocking the same when the actuators are operated by the type bars. The extremities *p'* of the rods *p* project high enough to engage the arms *p²* and operate the universal bar in both positions of the shift frame. As the arms *p²* are normally out of contact with the actuator rods *p* there is no friction between these parts when the shift frame is shifted. 80

Q represents a rearwardly extending arm or lever fixed to the universal bar for actuating the carriage escapement, to which this arm is connected by means not shown, and *R* represents a lever which is actuated by the arm *Q* and is connected by a link *r* to the vibrator lever for operating the latter. The lever *R* is pivoted at its rear end by a pin or rivet *r'* to the arm *Q* and has a hole *r²* through which the universal bar passes and 90 which is large enough to receive a sliding sleeve *r³* on the universal bar. This sleeve is adapted to be slid lengthwise on the universal bar to a position in which it projects through the hole *r²* in the lever *R* and its 95 conical end enters a corresponding recess in the hub of the arm *Q*. The lever *R* also has a hole *r⁴* adapted to receive a fulcrum pin *s* which is secured to a rod *S* and extends parallel with the universal bar. The 100 rod *S* is arranged to slide endwise parallel with the universal bar in guide holes in the brackets *n* and is provided with a forked collar or part *s'* which straddles a flange on the sleeve *r³* whereby the sleeve is slid 105 on the universal bar when the slide rod *S* is moved endwise. The collar *s'* is fixed on the rod and has a pin *s²* that depends therefrom into a hole in the inner end of a rod *s³* which is mounted to move endwise on the 110 underside of the top plate *a* and is connected by a crank or eccentric *t* to a rotatable operating shaft *T* extending to the front of the machine. By turning the shaft 115 *T* the rod *S* can be slid to move the sleeve *r³* into and the pin *s²* out of engagement with the lever *R*, or vice versa. The pin *s²* slides in a fixed lug or bearing *s⁴* on the shift frame and this prevents the rod *S* from turning and retains the pin *s²* in the 120 hole in the actuating rod *s³*, and compels the rod *S* and sleeve *r³* to move lengthwise only as actuated by the shaft *T*.

s⁵, Fig. 1, indicates a spring connecting the lever *R* to the shift frame for restoring the 125 universal bar and the connected levers to normal position after actuation. In the position of the parts shown in Fig. 8 the sleeve *r³* is seated in its hole in the lever *R* and the fulcrum pin *s* is withdrawn from its 130

hole in the lever. The lever R is then rigidly connected to the arm Q to swing therewith as one part, and produces the proper throw of the vibrator lever to move the lower field or portion of the ribbon to and from printing position. When the slide rod is moved to the position shown in Fig. 2 the lever R will swing on the pin s as a fulcrum, being actuated by the pivot r' connecting it to the arm Q. The hole r² in the lever R is large enough to allow the lever to swing on the fulcrum s when the sleeve r³ is moved out of the hole. The throw of the lever R will then be shortened to the requisite extent to vibrate the upper field or portion of the ribbon to and from printing position. This mechanism thus permits the use of a multi-color ribbon, or ribbon having two different kinds of fields or portions.

Since the universal bar, the carriage escapement, the ribbon vibrator and the connections between the same are all mounted on and shift with the shift frame there is no relative movement and friction between the parts when the platen is shifted. This construction also permits all of these parts to remain in place on the shift frame and be removed therewith from the machine. The top plate a of the main frame has an open central portion through which these parts pass when removing the shift frame. The push rod M and actuating rod s³ remain on the top plate a when the shift frame and the carriage are detached, and when the shift frame is returned the pin enters the hole in the rod s³ and the arm assumes the proper relation to the push rod M without attention. There is sufficient clearance between the pin and rod s³ and between the arm r' and push rod M to prevent friction between the parts when the shift frame is shifted.

U represents a type bar center guide which has legs rigidly secured in any suitable way to the top plate a of the main frame.

As shown in Figs. 2 and 3, the top plate a of the main frame is formed with a pair of rigid abutments V that rise therefrom at opposite sides of and close to the front projection d' of the shift frame. The projection does not touch the abutments when the shift frame is shifted up and down, but whenever the carriage in moving in either direction is brought to a sudden stop so as to cause the link or member F to spring or give, the projection d' is adapted to strike one or the other of these abutments and thereby prevent excessive strain on the link or member F.

While the ribbon vibrating mechanism, the means for changing the throw of the vibrator, the margin stop device and the releasing means therefor are believed to be of novel construction, they are not claimed herein, except in combination with the as-

sociated shifting means, the claims for these parts *per se* being reserved for a divisional application.

I claim as my invention:

1. In a typewriting machine, the combination with a platen carriage, and type bars, of a shift frame on which said carriage travels in letter spacing direction and which is mounted to shift transversely of the direction of travel of the carriage on three swinging arms which swing in planes substantially parallel to the plane in which the shift frame shifts and are disposed in triangular relation to each other with one arm between and in a different plane from the other two arms, the two outer arms being rigidly connected to swing together, and means for shifting said shift frame to place the platen in different printing relation to said type bars. 70

2. In a typewriting machine, the combination with a platen carriage, and type bars, of a shift frame on which said carriage travels in letter spacing direction and which is mounted to shift transversely of the direction of travel of the carriage on three swinging arms which swing in planes substantially parallel to the plane in which said shift frame shifts and are disposed in triangular relation to each other with two arms adjacent to the ends of the shift frame and the third arm substantially midway between the ends of the shift frame, and below said other arms, and shifting mechanism independent of said arms which acts on said shift frame substantially midway between its ends. 90

3. In a typewriting machine, the combination with a main frame, a platen carriage, and type bars each having a plurality of type, of a shift frame on which said carriage is movable in the direction of the length of the platen, a pair of rigidly connected arms pivotally connected at one end to said main frame and pivotally connected at their opposite ends to said shift frame at opposite sides of the center thereof, an arm located below the plane of said pair of arms and substantially midway between the ends of said shift frame and pivotally connected at said opposite ends to said main frame and said shift frame, and means for shifting said shift frame to place the platen in printing relation with one or another of the different sets of type, substantially as set forth. 110

4. In a typewriting machine, the combination with a main frame having a detachable top plate, a platen carriage, and type bars, of a shift frame on which said carriage travels in the direction of the length of said platen, a swinging member on which said shift frame is mounted and which is pivoted to said top plate, a swinging member which is pivoted to said main frame, said shift frame having a removable pivotal connec- 125

- tion with said second swinging member which permits the shift frame to be removed with said top plate from the main frame, substantially as set forth.
5. In a typewriting machine, the combination with a main frame, a platen carriage, and type bars, of a shift frame on which said carriage travels in the direction of the length of the platen; a cam device for shifting said shift frame transversely of the direction of travel of the carriage for changing the printing relation of the platen to the type bars, said cam device having a surface which shifts the shift frame and portions 10 which positively hold the shift frame from oscillating in both the normal and shifted positions, and a swinging member movably connecting said shift frame with the main frame, for maintaining said shift frame and carriage in operative position, substantially as set forth.
6. In a typewriting machine, the combination with a main frame, a platen carriage, and type bars, of a shift frame on which 15 said carriage travels in the direction of the length of the platen, a device located substantially midway between the ends of said shift frame for shifting the same transversely of the direction of travel of the carriage for changing the printing relation of the platen to the type bars, and three substantially parallel swinging members acting with said shifting device to form the entire support for the shift frame and carriage in either of their operative positions, substantially as set forth.
7. In a typewriting machine, the combination with a main frame, a platen carriage, and type bars, of a shift frame above said 20 main frame on which said carriage travels in the direction of the length of the platen, means for shifting said shift frame transversely of the direction of travel of the carriage, and counterbalancing springs arranged directly between the top of the main frame and said shift frame, said springs being arranged substantially perpendicular to the top of the main frame with one end bearing on said top and the other end 25 against the shift frame, substantially as set forth.
8. In a typewriting machine, the combination with a main frame, a platen carriage, and type bars, of a shift frame above said 30 main frame on which said carriage travels in the direction of the length of the platen, means for shifting said shift frame transversely of the direction of travel of the carriage, and counterbalancing springs for said 35 shift frame adjustably arranged on the top of said main frame beneath said shift frame, said springs being arranged substantially perpendicular to said top with their upper ends bearing against the shift frame, substantially as set forth.
9. In a typewriting machine, the combination with a main frame, a platen carriage, and type bars, of a shift frame on which the carriage travels in the direction of the length of the platen, a swinging member 40 pivoted to said main frame and pivoted to said shift frame at opposite sides of the center thereof, said shift frame having about midway between its ends a rigid part which projects therefrom in a direction 45 away from the carriage, a swinging member pivotally connected to said main frame and to said projection of the shift frame, and means for shifting said shift frame transversely of the direction of travel of the carriage, substantially as set forth.
10. In a typewriting machine, the combination of a main frame having a top plate, a swinging member pivotally mounted on said top plate, a shift frame mounted on 50 said swinging member to move up and down and having a rigid downward extension substantially midway between the ends of said shift frame passing through said top plate, means co-operating with said downward extension to hold the shift frame upright, a platen carriage supported by said shift frame and arranged to travel thereon in letter spacing direction, type bars each having a plurality of type, and means acting directly on said downward extension of the shift frame to shift said shift frame to place the platen in printing relation with one or another of the different sets of type 55 on the type bars.
11. In a typewriting machine, the combination of a main frame having a top plate, a swinging member pivotally mounted on the upper side of said top plate, a shift frame mounted on said swinging member to move up and down, and having a rigid downward extension substantially midway between the ends of the shift frame passing through said top plate, means co-operating with said downward extension to hold the 60 shift frame upright, a platen carriage supported on said shift frame and arranged to travel thereon in letter spacing direction, type bars each having a plurality of type, and means acting directly on said downward extension of the shift frame below said top plate to shift said shift frame to place the platen in printing relation with one or another of the different sets of type 65 on the type bars.
12. In a typewriting machine, the combination with a main frame having a top plate, a platen carriage, and type bars, of a shift frame above said top plate on which said carriage travels in letter spacing direction, means for shifting said shift frame up and down, and coiled counterbalancing springs for said shift frame seater in openings in said top plate and acting directly on 70 said shift frame.

13. In a typewriting machine, the combination with a main frame, a platen carriage, and type bars, of a shift frame above said main frame on which said carriage travels in letter spacing direction, means for shifting said shift frame up and down, and counterbalancing springs for said shift frame secured at one end to said main frame and having their opposite ends bearing against but disconnected from the underside of said shift frame, whereby the shift frame can be removed without disturbing said springs. 65
14. In a typewriting machine, the combination with a main frame, key actuated type-bars on said main frame, and a platen carriage, of a carriage shift frame on which the carriage is mounted and which is movable to place the platen in different printing relations to said type-bars, a carriage escapement and a universal bar mounted on and movable with said shift frame, and means actuated by direct impact of the type-bars for actuating said universal bar in the different positions of said shift frame. 70
15. In a typewriting machine, the combination with a main frame, key actuated type-bars on said main frame, and a platen carriage, of a carriage shift frame on which the carriage is mounted and which is movable to place the platen in different printing relations to said type-bars, a ribbon vibrating device and a universal bar mounted on and movable with said shift frame, and means actuated by direct impact of the type-bars for actuating said universal bar in the different positions of said shift frame. 75
16. In a typewriting machine, the combination with a main frame, key actuated type-bars on said main frame, and a platen carriage, of a carriage shift frame on which the carriage is mounted and which is movable to place the platen in different printing relations to said type-bars, a ribbon vibrating device and a universal bar mounted on and movable with said shift frame, and means actuated by direct impact of the type-bars for actuating said universal bar in the different positions of said shift frame, substantially as set forth. 80
17. In a typewriting machine, the combination with a main frame, key actuated type-bars on said main frame, and a platen carriage, of a carriage shift frame on which the carriage is mounted and which is movable to place the platen in different printing relations to said type-bars, a ribbon vibrating device, carriage escapement and universal bar all mounted on and movable with said shift frame, and means actuated by direct impact of the type-bars for actuating said universal bar in the different positions of said shift frame, substantially as set forth. 85
18. In a typewriting machine, the combination with a main frame, a platen carriage, and type bars, of a carriage shift frame which is movable to place the platen in different printing relations to said type-bars, a universal bar mounted on and movable with said shift frame, an actuator which is mounted on the main frame and is adapted to be actuated by a plurality of said type-bars, and means whereby said actuator operates said universal bar in the different positions of said shift frame, substantially as set forth. 90
19. In a typewriting machine, the combination with a main frame, key actuated type-bars mounted on said main frame, and a platen carriage, of a carriage shift frame on which the carriage is mounted and which is movable to place the platen in different printing relations to said type-bars, a swinging member on which said shift frame is mounted, a universal bar mounted on and movable with said shift frame, and means actuated by direct impact of the type-bars for actuating said universal bar in the different positions of said shift frame, substantially as set forth. 95
20. In a typewriting machine, the combination with a main frame, a platen carriage, and type-bars, of a shift frame on which the carriage is mounted and which is movable for moving said carriage in a direction transversely of the direction of the length of the platen, a universal bar which is mounted on and shifts with said shift frame, and an actuating device for said universal bar which is mounted on said main frame in position to be actuated by direct impacts of the type-bars and is disconnected from said universal bar, substantially as set forth. 100
21. In a typewriting machine, the combination with a main frame, a platen carriage, and type bars, of a shift frame on which the carriage travels, a swinging member on which said shift frame is mounted for shifting the carriage transversely of the direction of the length of the platen, and abutments on said main frame adapted to engage a part of said shift frame to prevent strain on said swinging member when the carriage is brought to a sudden stop, substantially as set forth. 105
- Witness my hand, this 22nd day of May, 1913.
- EMMIT G. LATTA.
- Witnesses:
- CHESTER W. REID,
OTTO A. SCHILLY.
